UNITED STATES PATENT OFFICE.

LEWIS WALASKY AND PAUL MROCKA, OF MAYFIELD, PENNSYLVANIA.

COUPLING-HOOK LOCK.

Application filed March 19, 1928. Serial No. 262,948.

This invention relates to new and useful improvements in mine car coupling hooks and aims to provide a locking device associated with the hook to prevent the same jumping 5 from the draw-head of the next adjacent mine car.

An important object of this invention resides in the provision of a coupling hook of this character that may be manufactured and 10 marketed at a cost but slightly greater than the usual hooks now in use the nature of the invention being such that the hook lock will by its own weight normally seek a locking position and that may be readily actuated to 15 locking position so that the hook may be manually detached from the draw-head of the next adjacent mine car.

With the foregoing and other objects in view as the nature of the invention will be 20 better understood, the same comprises the novel form, combination and arrangement of parts hereinafter more fully described, shown in the accompanying drawings and claimed.

In the drawings wherein like reference numerals indicate corresponding parts through 25 the several views:

Figure 1 is a fragmentary side elevation of the adjacent ends of a pair of mine cars showing my improved coupling hook in use,

Figure 2 is a side elevation partially in cross section of the hook per se,

Figure 3 is a top plan view thereof,

Figure 4 is a transverse section taken substantially upon the line 4—4 of Figure 3,

Figure 5 is a perspective of the lock member per se, and

Figure 6 is a fragmentary horizontal section of the hook taken substantially on the line 6—6 of Figure 2.

Now having particular reference to the drawings in Figure 1 there is disclosed fragmentarily a pair of adjacent mine cars designated generally A, A. The rear end of the foremost car is equipped with a length of

chain B to the free end of which is attached my improved coupling hook designated generally by the reference character 5 the nose portion of which is adapted for engagement within the usual draw-head C upon the adjacent end of the following car A. In carrying out the invention this hook 5 is formed directly back of the goose-neck end with a diagonal thickened portion 6 the opposite sides of which are formed with diagonally extending

channels 7—7. Slidably arranged within

these channels 7—7 are the elongated legs of an inverted U-shaped yoke 8 the bight portion of which is equipped with a pivotal handle 9. The lower ends of the legs 8 of this yoke are formed with forwardly extending inclined 60 toes 10—10 arranged through registering openings in which is a detachable pin 11.

The inner surface of the nose of the hook 5 in line with the forward edges of said channels 7—7 is formed with a notch 12 for receiving this pin 11 when the yoke drops downwardly to the position disclosed in Figures 1, 2 and 4 in which position the said yoke, being in back of the bight portion of the draw-head C will prevent the disengagement of the hook 70 from said draw-head.

By reason of the channel 7—7 in opposite sides of the thickened portion of the hook 5 are formed ribs and the lower ends of the ribs forwardly of the channels terminate above the lower edge of the thickened portion and are beveled so as to accommodate the toes 10—10 of the yoke legs while directly beneath the beveled ends of these ribs the shank of the hook is formed 80 with a notch 13 for receiving the pin 11 when the yoke is raised which will permit the yoke to be raised so that the lower end thereof will have a flush engagement with the lower surface of the hook shank enabling the hook to 85 be readily released from the draw-head C.

In view of the foregoing description when considered in conjunction with the accompanying drawings it will be apparent that we have provided a highly novel, simple and 90 useful lock hook coupling that is well adapted for the purpose heretofore designated and even though we have herein shown and described the invention as consisting of certain detail structural elements, it is nevertheless 95 to be understood that minor changes may be made therein without affecting the spirit and scope of the appended claims.

Having thus described our invention, what we claim is:

1. A coupling hook for mine cars comprising a shank, a bill on said shank having a portion thereof substantially paralleling the shank, the opposite faces of such shank being increased in thickness and having inclined guide channels formed therein, the inner face of the bill of the hook adjacent to the free end thereof being provided with an inclined keeper notch, a yoke member having its legs slidably arranged within said guide 110

channel, and a cross pin between the lower ends of the legs of the yoke for fitting in said keeper notch when the yoke is in its lowered position.

- 5 2. In a safety coupling hook for mine cars, a shank, a bill on said shank having a portion thereof substantially paralleling the shank, the shank having inclined guide channels formed in the opposite faces thereof and 10 a notch in its inner face, the inner face of the bill of the hook, adjacent to its free end being provided with an inclined keeper notch in alignment with the first mentioned notch,

and a yoke member having its legs slidably arranged within said channels, angularly extending feet formed on the lower ends of said legs, and a cross pin carried by said feet for engagement with the keeper notch when the hook is in its lowered position and for engagement in said first mentioned notch when the yoke is in its raised position.

15 20 In testimony whereof we affix our signatures.

LEWIS WALASKY.
PAUL MROCKA.
